COAL CUTTING MACHINE

John Jerome Cline, Clarksville, Ark.

Application July 14, 1939, Serial No. 284,543

2 Claims. (Cl. 262—30)

The device forming the subject matter of this application is a mining machine, and the invention aims to supply novel means for supporting and connecting sundry shafts of the machine, to improve the bearing structure, to secure proper balance in the machine, and to provide a device wherein movable parts will receive adequate lubrication.

It is within the province of the disclosure to improve generally and to enhance the utility of devices of that type to which the present invention appertains.

With the above and other objects in view, which will appear as the description proceeds, the invention resides in the combination and arrangement of parts and in the details of constructions hereinafter described and claimed, it being understood that changes in the precise embodiment of the invention herein disclosed, may be made within the scope of what is claimed, without departing from the spirit of the invention.

In the drawing, the invention is disclosed in a single, vertical sectional figure.

The general type of machine to which the present improvements are applied, is common and well known.

A power driven beveled pinion 1 imparts rotation to a beveled gear 2, rotating a first shaft 3 having a pinion 4, meshing with a rotatably mounted gear wheel 5, to which is connected a sprocket wheel 6, adapted to drive a cutter chain (not shown), movable along a cutter bar 7 connected at 8 to the frame F of the machine.

The frame F includes a partition 9, provided in its upper surface with a seat 10, shaped to receive, removably, a first ball bearing 11, the portion of the partition which forms the bottom of the seat 10 being supplied with drift holes 12, through which, the ball bearing 11 can be driven out of the seat 10, upon occasion.

One end of the shaft 3 is received within the bearing 11, the pinion 4 being carried by the shaft and overhanging the bearing 11, the sprocket wheel 6 constituting a portion of a cutting mechanism, driven by the pinion 4. The beveled gear 2 receives motion from the beveled pinion 1, the pinion 1 being operated by a power shaft 14, supported for rotation in the frame F.

The gear 2 includes a hub 15, surrounding the shaft 3 and engaging the upper end of the pinion 4. The upper end of the hub 15 and the adjacent portion of the shaft 3 are provided with cooperating recesses 16. A key 17 connects the hub 15 of the beveled gear 2 with the shaft 3. A ring

18 surrounds the shaft 3 and is located in the recesses 16. The ring 18 constitutes a retainer for the key 17.

A second ball bearing 19 surrounds the upper portion of the shaft 3 above the ring 18 and is located in the upper portion of the frame F.

A collar 20 is detachably assembled by securing elements 21, with the upper portion of the frame F, and may be considered as part of the upper portion of the frame. A closure 22 is threaded into the collar 20.

A force feed lubricating connection 23 is carried by the closure 22. The shaft 3 has a longitudinal bore 24, leading from the lubricating connection 23 to the bottom of the seat 10.

The construction as thus far described is such that the gear 2 is kept properly in mesh with the pinion 1, adequate lubrication being afforded, and the shaft 3 being supported, anti-frictionally, for rotation, the features above referred to giving long life to the mining machine, and rendering frequent renewals of parts unnecessary.

The eye 25 of the cutter bar 7 is attached by securing devices 26 to a tubular socket 27, having a foot plate 28, connected by securing members 29 to any accessible portion 30 of the mining machine. In the socket 27 is received the lower end of a fixed hollow shaft 31, connected, against rotation, to the socket 27, by a key 32.

The frame F includes an upper table 34, there being a space 35 about the table, a lid 36 giving access to the space 35. The table 34 carries an upper socket 37, which is closed at its top. In the socket 37, is removably mounted an inverted cup-shaped thimble 38. Near its lower end, the shaft 31 has an outstanding rib 39. A lower ball bearing 40 surrounds the shaft 31 and a packing 46 engages the lower end of the bearing 40 and is supported by a closure ring 43, to be described hereinafter.

The sprocket wheel 6 includes a hub 41 journaled in the part 9 of the frame F, within a packing 42. The closure ring 43 hereinbefore mentioned, is recessed into the bottom of the sprocket wheel 6 and is disposed about the lower socket 27. The gear member 5 is disposed at the upper end of the hub 41. A bushing 44 is located between the hub 41 and the ball bearing 40. Securing elements 45 connect the gear member 5, the bushing 44 and the closure ring 43. Above the ball bearing 40, a collar 46 is disposed about the shaft 31 and is located within the bushing 44.

A headed securing element 45' is seated in the part 30 of the machine and extends upwardly

through the fixed shaft 31, the thimble 38 and the socket 37. A nut 50 is threaded on the securing element 45 and engages the table 34. The securing element 45' has an axial duct 48, which leads laterally as shown at 49, through the shaft 31 and the collar 46 and furnishes lubricant to the ball bearing 40. An upper ball bearing 47 is disposed about the shaft 31, between the thimble 38 on the one hand and the collar 46 and the bushing 44 on the other hand. The bearing 47 receiving adequate lubrication from the cavity of the machine that exists above the partition 9.

The general construction is such that the advantages hereinbefore alluded to will be attained.

Having thus described the invention, what is claimed is:

1. In a mining machine a frame including a partition provided in its upper surface with a seat, a first ball bearing removably supported in the seat, a shaft having one end received within the bearing, a pinion carried by the shaft and overhanging the bearing, cutting means driven by the pinion, a gear including a hub surrounding the shaft and engaging the upper end of the pinion, the upper end of the hub and the shaft being provided with cooperating recesses, a key connecting the hub of the gear with the shaft, a ring surrounding the shaft and located in the recesses, the ring constituting a retainer for the key, a second ball bearing surrounding the upper end of the shaft and engaging the ring, a closure detachably assembled with upper portion of the frame and exerting pressure

on the second ball bearing, and a lubricating connection carried by the closure, the shaft having a longitudinal duct communicating with the lubricating connection and leading to the bottom of the seat.

2. A mining machine comprising a frame having fixed upper and lower sockets, a thimble in the upper socket, a fixed tubular shaft having its ends received in the thimble and in the lower socket, the shaft having an outstanding abutment rib, a lower ball bearing engaging the rib, a cutter-driving sprocket wheel about the bearing and including a hub spaced from the bearing and journaled in the frame, a closure ring on the bottom of the sprocket wheel and disposed about the lower socket, a gear member at the upper end of the hub, a bushing between the hub and the ball bearing, a securing element connecting the gear member, the bushing and the closure ring, a collar about the shaft and located within the bushing, the collar engaging the lower ball bearing, an upper ball bearing about the shaft and engaged between the collar and the thimble, and a tightening device extended through the shaft and engaging the lower part of the frame and the upper socket, the tightening device having a longitudinal oil duct leading laterally through the shaft and the collar to the inner surface of the bushing, and constituting means for lubricating the lower ball bearing.
